UNITED STATES PATENT OFFICE.

FRANCOIS ROCHEFORT, OF PARIS, FRANCE.

TWO-STROKE INTERNAL-COMBUSTION ENGINE.

Application filed September 22, 1925, Serial No. 57,917, and in France September 25, 1924.

Two-stroke engines without poppet valves are known, having total or partial distribution by reciprocating or rotating slide-valves or which combine those two systems together.

In certain motors with total distribution the slide valve forms the inner part of the engine-cylinder and of the scavenging pump cylinder, the pistons moving in this part of the cylinders.

In this arrangement, the slide valve must have the same length and diameter as the cylinders, which renders it heavy. Since, further, it forms the working chamber for the combustion gases, it must withstand the high pressure and temperature of these gases.

This kind of distribution or timing does not allow high speeds of rotation to be obtained, by reason of the inertia of the slide-valve; it renders lubrication difficult because of the temperature of the walls, and, by not allowing very accurate adjustment of the distribution, it limits the global efficiency of the motor to a low value.

In other motors, the valve is rotary and carried outside the working cylinder, at the height of the ports for the entry of scavenging air. Although the temperature of the walls of the slide valve may be less in this arrangement than in that which has just been mentioned, it is still too high. Moreover, this arrangement, being less gas-tight, allows the passage between its wall and that of the cylinder in which it rotates, of gases which have expanded but are still at a high temperature, which has for effect to cause the deposit upon these walls, of carbon residues resulting from the incomplete combustion of the gases, these residues rendering the working less certain by giving rise to the dangers of the slide valve seizing in its seat. The lack of gas-tightness of the arrangement causes also losses of efficiency in the scavenging pump. The arrangement adopted does not permit of accurate and precise adjustments of the opening and closing points of the ports for the admission and the discharge of the air to and from the scavenging pump, and the throttling of the air or gases passing through the ports is increased, from the very fact that the circumferential speed of the rotary valve is constant, if it be wished to retain reasonable dimensions for this valve. Last-

ly, ports having different functions are in the same plane, so that it is not possible to avoid or to counterbalance the side thrusts on the part of the burnt gases still under pressure when the working piston uncovers the scavenging ports.

There exist, it is true, engines in which the distribution is ensured for each working cylinder by two or three separate reciprocating slide valves or by slide and poppet valves having independent functions and movements. This arrangement has the advantage of permitting accurate adjustments but it enormously complicates the operating devices, the piping, and the joints, and renders laborious the construction and maintenance of such an engine which it is difficult to build conveniently.

The present invention has for its object an internal combustion engine working on the two-stroke cycle preferably with direct injection of the fuel into the working cylinder.

The construction of this engine enables to be suitably ensured:—

(1) The correct timing for the suction and delivery of air into and from the scavenging pump.

(2) The precise adjustment of the moment of introduction of the scavenging air into the engine cylinder, after complete expansion of the burnt gases.

(3) The perfect filling of the cylinder volume with pure air and, for certain uses, the supercharging of the working cylinder by a retarded closing of the inlet ports, well after the closing of the exhaust ports for the escape of the burnt gases.

In this way the passive resistance are reduced to the minimum, complete evacuation of the burnt gases is effected, by a more efficient scavenging, and a higher specific efficiency of the engine is obtained.

The engine according to the invention is characterized by the use for each working cylinder of a single cylindrical distributing piston valve fitted with piston rings, and having rectilinear reciprocating movement in a small cylinder placed parallel with the working cylinder and communicating therewith only by the ports for the admission of scavenging air, formed in the base, in order that the walls of the distributor slide valve and of its cylinder shall be never in contact

with gases of high pressure and temperature.

This distributor slide valve performs the same number of strokes as the working piston, its driving crank revolving at the same speed 5 as the engine shaft, but it is timed to follow after the driving crank shaft in order to obtain a better adjustment of the distribution.

In case it is employed in slow running engines, this slide valve may be provided 10 inferiorly with an obturator diaphragm which obviates a loss of efficiency occasioned by the resistance which would result from the setting up of currents in the opposite direction at the opening of the pump delivery outlets 15 while the pressure of the air contained in the scavenging collector is still higher than that which exists in the air pump at the commencement of its delivery stroke.

This obturator becomes unnecessary when 20 the engine has to run at high speeds, the inertia of the air being then sufficient to overcome the phenomenon indicated.

The cylinder of the distributor slide valve is provided with two annular chambers, completely surrounding the distribution ports, in 25 order to avoid lateral thrusts of the slide valve against its cylinder wall; these annular chambers further permit of verifying in a very precise manner the points of opening 30 and closing of the ports by the distributor slide, in order to adjust their position for a given position of the driving crank and according to the periods of the cycle, a correcting device being interposed for that purpose between the slide valve and the connecting rod which operates it.

The arrangement of the annular chambers around the ports enables large sectional areas to be provided for the passage of the scaveng- 40 ing air, whilst requiring a very restricted stroke for the slide valve which can be of very small dimensions.

In the case of aviation motors, there is provided upon the control mechanism for the 45 slide valves, between the driven gear wheel and the timing shaft, an arrangement for altering the angular setting of the distributor slide valves relatively to the engine shaft, in order to vary the volume of air delivered by 50 the scavenging pump and to regulate the filling of the working cylinder volume for the purpose of maintaining the compression more or less constant, at the various altitudes at which the engine is required to work, the 55 characteristics of the air pump being naturally selected with a view to the rational utilization of this kind of adjustment.

The actuation of the slide valve is positive 60 in both directions and is very easily applied to the construction of directly reversible motors (for example for marine engine sets) by means of the employment of an angular setting adjustment similar to that which has been indicated above. The actuation can be 65 effected by any one of the known means, such

as connecting rod and crank operated by direct gear wheels or chains preferably of the silent type.

The distributor slide valve having very small dimensions in relation to those of the working piston and consequently very low inertia, it is easy to attain the high rotational speeds necessary in the operation of high-efficiency, light-weight motors.

The annexed drawing shows by way of example an engine constructed according to the invention.

Figure 1 is a section through a vertical plane perpendicular to the crank shaft.

Figures 2 to 10 reproduce Figure 1 dia- 80 grammatically on a smaller scale and are intended to illustrate the various phases in the working of the engine.

As shown on the drawing (Figure 1), the motor comprises a cylinder C—C¹ in which there reciprocates a piston of two corresponding diameters P P¹ of one of the known types provided with a deflector d at its top.

Upon the side of the engine cylinder C and at its lower part is arranged a small cylinder C² in which the distributor slide-valve P² recipro- 90 cates, being actuated by a small connecting rod b and a small timing or distribution crankshaft m, driven at a speed equal to that of the engine shaft M either by direct gearing or by a silent chain, as shown in Figure 1.

A chamber A is in constant communication with the atmosphere by means of a gauze or screen intended to prevent foreign matter from entering the air pump. The latter is formed by the lower large-bore cylinder C¹ and the corresponding piston P¹. Ports L allow the cylinder C¹ to communicate either with the atmosphere through the chamber A or with the collector c, according to the position of the bottom end of the slide P² and of the ports L¹ spaced around the circumference of the wall of the distributor slide; ports L² spaced around the wall of the small cylinder C² effect communication of the latter with the working cylinder C by the intermediary of the ports L³ for the admission of scavenging air.

Other ports L⁴ formed in the wall of the working cylinder C allow the release and exhaust of the burnt gases into the atmosphere at the end of the stroke of the working piston P.

This exhaust takes place into an expansion chamber, energetically cooled, and afforded 110 by the exhaust manifold E.

A device for injecting and atomizing the fuel is arranged at J; at I is arranged an electric ignition device to ensure immediate starting from cold. An igniting bulb plate, T raised to a high temperature by the combustion of the gases, provides the normal ignition. It may even permit rapid starting by causing ignition by external heat if the small bulb situated in the centre of the plate be 125 130

heated. This bulb can be brought to a dull red heat in a very short time either by the aid of a cartridge of suitable material or by using a small blow pipe mounted upon the engine for that purpose.

The distribution shaft m has its crank offset by an angle of about 100° rearwards in relation to the crank of the engine shaft M and to the direction of rotation of this latter, in order to obtain port opening and closing points as correct as in the case of independently operated poppet valves and to offer the largest passage areas for the scavenging air at the moment of maximum speed of the piston P^1 of the scavenging pump as well as during the periods of gas scavenging and of cylinder-charging after the closing of the exhaust ports L^4 .

The working of this engine is as follows:—
20 The engine being started in the direction of the arrow in Figure 1, the piston commences its working stroke (period of expansion after ignition); it has then passed the top dead centre, the crank pin of the engine shaft has
25 passed the vertical axis by some few degrees, the slide valve P^2 just closes the ports L communicating with the interior of the cylinder pump C^1 , that is to say this closure takes place with a certain lag in order to allow the pressure of the air enclosed in the clearance or neutral space of the scavenging pump, to balance the pressure obtaining in the scavenging air collector c , which has just been charged with pure air at a slight pressure. The slide-valve P^2 rises rapidly, by reason of the setting of the cranks, while the piston P^1 passes through a small fraction of its downward stroke, creating a slight fall of pressure above it.

40 The slide P^2 still rising (Figure 2), its base uncovers the ports L , and a current of cold air caused by the fall of pressure created in the cylinder C^1 , passes in rapidly through the chamber A and the ports L .

45 The piston P^1 continues to descend with increasing speed while the slide, still rising, reaches the end of its stroke, wholly uncovering the ports L in order to facilitate the filling of the air pump (Figure 3).

50 The working stroke continuing, the engine piston P next uncovers the top of the ports L^3 for the admission of scavenging air but, at this moment, the slide valve P^2 closes these ports and cuts off any communication with the collector c , leakage being prevented by rings above and below the ports L^2 of the small cylinder C^2 .

55 The burnt gases, having expanded in the engine cylinder C , penetrate for a very short time into the space comprised between the ports and the annular chamber which surrounds the small cylinder C^2 ; there is no lateral thrust upon the slide valve, because the pressure of the gases acts uniformly around the whole circumference.

The expansion stroke continues until the working piston P uncovers the exhaust ports L^4 ; at this moment, the distributor slide valve P^2 has passed the top of its upward stroke and commences to descend. The working piston 70 completes the opening of the exhaust ports L^4 (Figure 5), and the burnt gases expand rapidly into the exhaust manifold E communicating with the atmosphere. When the burnt gases are completely expanded, there 75 is a contraction of the gases, and a certain fall of pressure is created in the cylinder C . At this instant (see Figure 6), the distributor slide valve which is well upon its descending stroke, suddenly uncovers the ports L^2 of the 80 small cylinder C^2 ; the air compressed in the collector c on the preceding stroke, expands and rushes into the engine cylinder, being drawn thereinto by the fall of pressure due to the exhaust. This air is directed towards the 85 top e of the cylinder head by the deflector d formed upon the top of the working piston P and drives the burnt gases before it.

The momentum of the scavenging air is utilized to its maximum by means of a careful 90 adjustment of the point of opening of the ports L^2 , which adjustment causes the expansion of the compressed air for scavenging to coincide with a pronounced fall of pressure in the exhaust. There is thus obtained a complete evacuation of the inert gases whilst limiting the duration of the period of scavenging (the exhaust pipe being determined and designed to that end), which constitutes a 95 great advantage for high speed engines.

100 As the main piston P^1 approaches the end of its stroke, the air pump has just finished its period for admitting cold air; the slide valve commences to close the ports L (Figure 6). Continuing its stroke, the engine piston reaches the bottom centre, but the slide valve closes the ports L with a slight lag; the supply into the pump cylinder C^1 continues through the openings o uncovered at the end 105 of the stroke by the piston P^1 and communicating with the atmosphere by the extremities of a collector A^1 formed in the crank chamber of the engine and at the upper part thereof. These openings o provide for a delay or lag 110 in the closing of the admission of air for the scavenging pump, in order to have a perfectly full charge (Figure 7).

115 The working cylinder is at this moment in the very midst of scavenging the burnt gases. Continuing its stroke, the working piston passes the lower dead centre and commences to rise; the openings o are covered again by the piston P^1 , the distributor slide valve having already closed the ports L .

120 The piston P^1 in its ascending stroke slightly compresses the air admitted into its cylinder C^1 , whilst the slide valve still descending brings the ports L^1 formed in its periphery (Fig. 8) into position opposite the ports L of the small cylinder C^2 and of the air pump 125 130

which is then at the beginning of its stroke for delivering into the collector *c* in which the scavenging air is to be stored.

In the case of a slow running engine, the ports *L*¹ are separated from the upper opening of the piston valve *P*² by a disc valve *D*, the lift of which is limited by a stop piece or head *D*¹ (these two devices are shown in broken lines in Fig. 1). The disc valve *D* will be lifted as soon as the pressure of air in *C*¹ is greater than that which exists in the collector, the latter thus continuing to be supplied. The inertia of this valve facilitates its opening as well as its closing.

15 The working cylinder *C* is represented in Fig. 8 in full scavenging operation, the engine piston being then on its upward stroke; when it closes the exhaust ports *L*⁴, the scavenging phase is ended, the motor piston reaching the position indicated in Fig. 9.

The ports *L*³ intended for the admission of air to the working cylinder remain still open for a certain time in order to allow the cylinder *C* to be properly charged; the air pump is during this time in full delivery and contributes to the filling of the working cylinder by feeding the collector *c*.

The engine piston, continuing its upward stroke, closes the admission ports *L*³ when the pressure of air contained in the cylinder *C* is almost in equilibrium with that which exists in the collector *c* (Fig. 10).

35 The effective compression thereupon commences in the engine cylinder *C* whilst the collector *c* becomes charged with fresh air at low pressure, delivered by the air pump, in sufficient quantity for the next scavenging operation.

40 Before the working piston reaches the end of the compression stroke, the injecting-atomizing device fitted at *J* introduces the charge of fuel which is finely atomized and diffused in the pure air compressed by the working piston. In these conditions, mixture is rapidly effected, ignition occurring at the end of the stroke and creating a rapid rise of pressure of the gases which afterwards expand doing useful work.

50 The piston *P* after passing the top dead centre, commences its working or expansion stroke; the distributor slide valve *P*² rises and closes the ports *L* at the end of the delivering stroke of the air pump and the cycle recommences as has been described.

It will thus be seen that in this engine:— 55

(1) The burnt gases are completely expanded before the introduction of the scavenging air in such a way as better to utilize the momentum of the compressed air with a view to scavenging and in consequence to 60 accelerate the evacuation of the burnt gases whilst reducing to a minimum the losses of air by the mixture of the latter with these gases.

(2) The evacuation of the burnt gases is 65 complete by reason of the introduction of a volume of fresh air greater than the total capacity of the working cylinder, that is to say than the volume swept by the working piston increased by the clearance space of the 70 combustion chamber.

(3) Perfectly full charging of the working cylinder with fresh air and in certain cases supercharging are obtained by the conjunctive action of a considerable delay or 75 lag in the closing of the inlet ports *L*³ and of those of the air pump which delivers into the scavenging air collector during the closing of these ports.

(4) Scavenging is effected by fresh and 80 cold air, which is not saturated with vapours of the lubricating oil contained in the crank chamber, because this air does not pass into the latter.

The fuel being introduced into the engine 85 cylinder only well after the closing of the ports, which is effected in the middle of the compression stroke, there is no loss of fuel through these ports. It is however to be understood that the application of the invention is not limited to engine having direct injection of fuel only.

What I claim is:—

In an internal combustion engine including a cylinder having an inlet port, a piston 95 working in said cylinder, an air supply chamber, and a valve for controlling the supply of air from said chamber to the cylinder, in combination with a piston valve for controlling the supply of charge through the inlet port, the said piston valve moving for approximately a half-stroke with respect to the piston and attaining its maximum linear speed at the period of admission of air from said air supply chamber to the cylinder. 100 105

In testimony whereof I have signed my name to this specification.

FRANÇOIS ROCHEFORT.
